CLAIM

The ornamental design for a side element of a shoe upper, as
shown and described.

DESCRIPTION

FIG. 1 is a perspective view of a side element of a shoe upper
showing my new design;

FIG. 2 is a side view of the side element of a shoe upper
shown in FIG. 1;

FIG. 3 is a front view of the side element of a shoe upper
shown in FIG. 1;

FIG. 4 is a rear view of the side element of a shoe upper
shown in FIG. 1; and,

FIG. 5 is a top view of the side element of a shoe upper
shown in FIG. 1.

The uneven broken line immediately adjacent to the shaded
area represents the bounds of the claimed design. All other
uneven broken lines represent the remaining portion of the
shoe. The uneven broken line representations in FIGS. 1-5
are for illustrative purposes only and form no part of the
claimed design.
